UNITED STATES PATENT OFFICE.

CHARLES FINIGAN, OF GIBSONIA, PENNSYLVANIA.

SHEET-FEEDING MACHINE.

Application filed November 22, 1924. Serial No. 751,552.

To all whom it may concern:

Be it known that I, CHARLES FINIGAN, a citizen of Great Britain, and a resident of Gibsonia, in the county of Allegheny and State of Pennsylvania, have made a new and useful invention in Improvements in a Sheet-Feeding Machine, of which the following is a specification.

The invention relates to apparatus for feeding metal plates from a stack, which rises step by step, to the feed rolls in advance of a coating or lithographing machine. It has for its principal objects, the provision of improved means, whereby the plates may be fed from the pack at a high rate of speed and whereby the separation of the top sheet from the pack therebeneath is insured, so that when operating at even a high rate of speed, only a single sheet is separated and fed forward in each case. A further object is the provision of means whereby packs containing a maximum number of sheets may be handled by the vertical lifting device, and whereby the packs may be shifted on their bases from transfer trucks to such device conveniently and rapidly, thus reducing the labor of looking after the machine to a minimum, and also reducing to a minimum the time lost by the machine while a fresh pack of plates is being placed upon the lifting device after the pack upon such device has been exhausted. One embodiment of the invention is illustrated in the accompanying drawings, wherein:

Figure 1 is a front elevation of the machine. Fig. 2 is a side elevation looking at the right side of the machine of Fig. 1. Fig. 3 is a vertical section on the line III—III of Fig. 4. Fig. 4 is a plan view. Fig. 5 is a rear elevation. Fig. 6 is an end elevation looking at the left side of the machine of Fig. 1. Fig. 7 is a vertical section on the line VII—VII of Fig. 4. Fig. 8 is a diagrammatic view showing the electrical connections. And Figs. 9 and 10 are detail views of the adjustable crank employed, Fig. 10 being a section on the line X—X of Fig. 9.

Referring to the drawings, 1, 2 are side plates of the machine, 3 is a transverse connecting plate at the base of the side plates, and 4 and 5 are a pair of wood bars or tie members extending transversely of the side plates at their upper ends. The side plate 1 is provided with a pair of brackets 6 and 7

for supporting the motor 8 and the air pump 9.

The rear side of the framework of the machine is open, as indicated in Fig. 5, to permit of the insertion of the pack of metal plates 10 through the side, such pack being shown as supported on a standard wood base made up of the boards 11 secured to the transverse bars 12. The base with its pack of plates is brought to this position on a truck, and transferred to the elevating brackets 13, 13, such brackets being provided with end portions 14, 14, guided for vertical movement in suitable guideways 15, 15 and provided with vertical threaded openings, 70 through which the feed screws 16 and 17 extend. These screws are supported in suitable thrust bearings 18, 18 at their lower ends, and in the bearings 19, 19 (Fig. 3) adjacent their upper ends, and serve by their rotation, as hereinafter described, to feed the pack upward step by step as the top sheets are removed one after the other.

Forward of the machine is the table 20, or other transfer means, leading to the coating or lithographing machine, in which the plates of the pack are to be decorated or coated, and in line with the upper surface of such transfer means or table are the usual feed rolls 21 and 22. The rolls 21 (Fig. 1) are mounted on the driven shaft 23 journaled at its ends in the side plates 1 and 2, while the rolls 22 are mounted on a pair of arms 24 (Fig. 3). These arms are secured to the rod 25, also mounted at its ends in the side plates 1 and 2. The shaft 23 carries at its end a spur gear 26, which is driven from a pinion 27 (Fig. 1) carried by the shaft of the motor 8.

Extending transversely of the machine 95 above the pack 10, adjacent its forward side (Fig. 3), is the shaft 28, which carries the electro-magnet 29, provided with the core 30, having the adjustable tips 31, 31. The shaft 28 is mounted in bearing blocks 32. This shaft is provided with a gear 34 at its end meshing with the gear 26.

The feed screws 16 and 17, by means of which the pack 10 is lifted step by step are driven from another transverse shaft 35 journaled in the side plates 1 and 2, and carrying at its ends the bevel gears 36, 36, which engage the gears 37, 37 carried at the upper ends of the screws. Upon one end of the shaft is secured the ratchet wheel 38

(Fig. 6), and this wheel is given a step by step movement of rotation by the pawl 39 carried by the arm 40. The arm 40 is oscillated by means of a crank 41, to which the 5 arm 40 is connected by the rod 42, and the crank itself is driven from the shaft 28 through the intermediary of the spur gears 43 and 44, the latter being carried by the stub shaft 45 (Fig. 9) upon which the crank 10 41 is carried. The throw of the crank is preferably made adjustable, as indicated in Figs. 9 and 10, in order to vary the feed of the screws 16 and 17 depending on the thickness of the sheets of the pack. This adjustment 15 is accomplished by slotting the crank and mounting the crank pin 46 therein, as illustrated, with locking nuts 47 to hold such pin in adjusted position. The transverse shaft 35 may also be operated by hand by 20 means of the crank 48 carried on the other end of the shaft (Fig. 2), the pawl 39 being disengaged at such time.

The sheets are lifted preliminary to being fed ahead by the magnet 28, by the electro-magnets, 49, 49, 49, 49 preferably, but not necessarily four in number arranged with their poles above the corners of the pack as indicated in Fig. 4, such magnets being carried by the bolts 50 extending through the 30 slots 51 in the cross bars 4 and 5, thus providing for the adjustment of the magnets vertically and also laterally to vary their lifting effect and to suit sheets of different sizes. The bars 4 and 5 are also mounted 35 for adjustment toward and from each other. The windings of these magnets are energized at timed intervals to lift the sheets of the pack, so that they may be fed forwardly by the rotating magnet 29, at which time the 40 circuit through the windings of the magnets 49 is broken, so that the plate is free to move forward.

In order to promote the separation of the top sheet of the pack from the sheet next 45 beneath when the magnets 49 act to lift such top sheet, a stop member 52 is employed above the central portion of the top sheet at the extreme rear edge thereof. This member is carried by the bar 4 (Fig. 3) and 50 is pressed down yieldingly against the top sheet by the spring 53. When the magnets 49 are energized, the four corners of the top sheet are raised, but the stop 52 pressing against the rear edge of the sheet prevents 55 the upward movement of such edge at this point, so that the sheet is flexed by the magnets instead of being lifted bodily, and the tendency of the air to lift the second sheet with the top sheet is reduced, the pressure 60 of the stop also tending to prevent the second sheet from moving forward with the top sheet when such sheet is dragged forward by the rotating magnet 29.

A further means for reducing the tendency of the second sheet to lift with the

top sheet is the provision of air blasts directed against the upper edges of the pack on all four sides of such pack. The air for this purpose is supplied through the two nozzles 54 at the front of the pack (Fig. 1), 70 the four nozzles 55 at the sides of the pack (Fig. 4), and the four nozzles 56, 56 and 57, 57 (Fig. 4) at the back of the pack. All of these nozzles with the exception of 56, 56 are supplied with continuous blasts from the 75 air pump 9 driven from the motor 8 by means of the belt 58, suitable piping 59, 60, 61, 62, 63, 64, etc. as illustrated being provided to convey the air to the nozzles. The nozzles 56, 56 are supplied with intermittent 80 blasts so timed that the air is applied just after the top sheet of the pack is lifted by the magnets 49, thus providing a body of air tending to support the sheet and facilitate its forward movement. This function 85 is accomplished as indicated in Fig. 7 by the use of a flexible feed pipe 64^a and the pinching lever 65 pivoted at 67 and operated by the cam 66 on the rotating shaft 28. The rubber pipe 64^a constitutes the connection 90 between the pipe 62 (Figs. 1 and 7) and the pipe 63 to which the nozzles 56, 56 are connected. The lever 6 carries an adjustable 95 wearing shoe 69 for engaging the cam 66.

The windings of the lifting magnets 49 are energized intermittently, so that after a sheet is lifted from the pack, it is released from the magnets in order to permit the rotary magnet 29 to carry it forward without any retardation from the lifting magnets. The construction for supplying current to the magnet windings is shown diagrammatically in Fig. 8. The rotating shaft 28, which carries the rotating magnet is hollow, and is provided with a sleeve of 100 insulating material at one end, on which are mounted the continuous shoes 70 and 71 and the pair of spaced shoes 72 and 73. The shoes or collars 70 and 71 are connected by the wires 79 and 80 to the winding of the 105 magnet 29, while the spaced shoes or collars 72 and 73 are each connected by a wire 81 to the wire 80. Three brush strips, 74, 75 and 76 bear against the collars, and other 110 connections 77, 78, 82 and 83 are arranged as illustrated, 77 and 78 being the mains carrying the supply current. Two circuits 115 are in this manner provided, the first, a continuous one through the winding of the rotating magnet 29 and including the brush strip 74, the shoe 70, the wires 79 and 80, the shoe 71 and the brush strip 75; and the second an interrupted one through the windings of the four lifting magnets 49, including 120 the brush strip 74, the shoe 70, the wires 79 and 80, the wires 81 to the shoes 72 and 73, the brush strip 76, and the wires 83 and 82. A suitable resistance 84 in the connection 78 insures that a part of the current 125 from the wire 80 shall pass through the connection 130

nections 83 and 82 and the windings of the magnets 49 rather than it should all pass through the collar 71 and brush 75 to the connection 78.

5 The method of operating the machine is as follows: The stacks of plates to be coated or lithographed are arranged in large packs, such as 10 upon standard commercial bases, and one of these is carried upon a truck into 10 the position shown in Figs. 1 to 6 just above the lifting shelves or brackets 13, 13 (Fig. 5), which may then be moved up by actuating the hand crank 48 to lift the base from the truck. The motor 8 is then started and 15 the pack is fed upward step by step, the motor operating through the gearing connections heretofore described and including the ratchet and pawl 38, 39 (Fig. 6) heretofore described. After each lifting step, 20 the four magnets 49 are energized to lift the top sheet from the pack. This lifting effect is facilitated by the continuous air blasts from the nozzles 54, 55 and 57, which tend to break the vacuum between the top 25 plate or sheet and the one next below, and this is further augmented by the air blasts from the nozzles 56, 56 which are applied after the sheet is lifted. The action of the magnets 49 and air blasts is a priming one, 30 in order to provide a film of air between the top plate and the one next below, so that such top plate may be moved forward without frictional resistance. The make and break device (of Fig. 8) is so timed with 35 respect to the rotating feed magnet that the top plate is lifted by the magnets and released as the tip 31 of the pole of the magnet 29 (moving in a clockwise direction) approaches the vertical position of Fig. 3. The 40 forward edge of the sheet is drawn upward sharply at this moment into contact with the tip 31, and the top sheet (now out of contact both with the poles of the magnets 49 and the sheet beneath) is carried forward 45 between the feed roll 21 and 22. The pole of the magnet 29 automatically frees itself from the sheet, as the strength of this magnet is not sufficient to tilt the plate from its horizontal position. The operation, as 50 just described, is repeated when the other pole tip of the rotating magnet core approaches vertical position, the one rotation of the shaft 28 serving to secure the feeding of two sheets, and the make and break of 55 the circuit through the windings of the lifting magnets 49, being timed accordingly. The same result as to rate of feed might, of course, be secured with a feed device having only a single feed pole, by doubling the 60 speed of rotation of the shaft 35 carrying the magnet, or by increasing the number of magnets on the shaft 28 and decreasing its speed of rotation. The number of lifting magnets might also be increased or decreased 65 under varying conditions, although the num-

ber shown and described, constitutes the preferred arrangement. All of the magnet poles may be coated or plated with a non-magnetic material to prevent any adherence to the plates.

70 After the pack 10 has been exhausted, the pawl 39 is released from the ratchet wheel 38, the empty base is removed from the machine, and the screws 16 and 17 are run backward from the hand crank 48 to bring 75 the lifting brackets 13 again to their lower-most position, when a new base carrying a pack of plates is positioned on such brackets, and the operation as heretofore described is 80 repeated.

The machine may be operated so as to feed much more rapidly than is possible by hand, and only a fraction of the time of one attendant is required to keep the machine in 85 operation. By using the standard bases and constructing the machine so as to receive them through the open side, a pack of maximum vertical dimension may be supplied to the machine at one time, and with slight effort on the part of the operator, as standard trucks can be shoved beneath the bases carrying the stacks, and no lifting of the stacks is required after they are placed on the bases. By proper adjustment of the 90 magnets and the mechanism cooperating therewith, a feed is secured which is positive and reliable, only a single plate being fed at a time and the plates in the pack below the top one are not subject to lateral movement 95 from their proper positions, this result being 100 due in a considerable degree to the manipulation of the air blasts as heretofore explained, and to the use of the stop member 52 which holds down the top plate at its rear edge and causes the flexing of such top 105 plate under the influence of the lifting magnets and preliminary to the forward feed of the plate. A further advantage incident to the use of the apparatus, is the fact that the contact of the plates with the electromagnetic devices is relatively light and no marring of the surfaces of the sheets results. The rotating magnet 29 with its spaced feeding poles arranged to strike the sheets at 110 their extreme forward edges provides a positive feed, incident to the impact effect, and at the same time, reduces any marking effect to a minimum and produces such marking at a location on the sheets where it does no harm. Other advantages of the construction will be apparent to those skilled in the 115 art.

What I claim is:

1. The combination with a vertical feeding device for a pack of plates and feed members in advance of such device, of feed means comprising electromagnetic lifting means above the pack, a rotating magnet also located above the forward portion of the pack and having a pole extending radial- 120 125 130

- ly with respect to the axis of rotation of the magnet and adapted by its rotation to strike the plate lifted from the pack by said lifting means and feed it forwardly, and 5 automatic means for intermittently making and breaking the circuit energizing said electro-magnetic means.
2. The combination with a vertical feeding device for a pack of plates and feed members in advance of such device, of feed means comprising electromagnetic lifting means above the pack, a driven axle above the pack extending transversely of the forward end thereof, a plurality of magnets mounted 10 thereon with their poles spaced apart and extending radially with respect to said axle for striking the plates and moving them forwardly after they are lifted by said lifting means, and automatic means for intermittently making and breaking the circuit energizing said electromagnetic means.
3. The combination with a vertical feeding device for a pack of plates and feed members in advance of such device, of lifting means adapted to operate at timed intervals to apply lifting force from above to successively lift the top sheets from the pack and release them, and a rotating magnet also located above the forward portion of 15 the pack and having a pole extending radially with respect to the axis of rotation of the magnet, the rotation of the magnet being so timed that it will engage the top plate to feed it forward when said lifting means release said sheet after lifting it from the pack.
4. The combination with a vertical feeding device for a pack of plates and feed members in advance of such device and an 20 electric circuit, of feed means comprising a pair of electromagnetic lifting devices in operative relation to said circuit and located above the rear portion of the pack adjacent the side edges thereof, a stop device also 25 above the rear portion of the pack but adjacent the central portion thereof to maintain the central portion of the top sheet at a lower level than its side edges when it is lifted by said devices, a rotating magnet also 30 located above the pack adapted by its rotation to feed the top plate of the pack forwardly, and automatic means for intermittently making and breaking the circuit energizing said electromagnetic means.
5. The combination with a vertical feeding device for a pack of plates and feed members in advance of such device, of feed means comprising electromagnetic lifting means above the pack and an electric circuit 35 for energizing said electro-magnetic lifting means, a rotating magnet also located above the pack adapted by its rotation to feed the top plate of the pack forwardly, automatic means for intermittently making and breaking the circuit energizing said electromagnetic means, and means intermittently applying blasts of air beneath the top sheets of the pack as they are successively lifted by 40 said electromagnetic means.
6. The combination with a vertical feeding device for a pack of plates and feed members in advance of such device, of feed means comprising electromagnetic lifting means above the pack and an electric circuit for energizing said electro-magnetic lifting means, a rotating magnet also located above the pack adapted by its rotation to feed the top plate of the pack forwardly, automatic means for intermittently making and breaking the circuit energizing said electromagnetic means, and means for continuously applying air under pressure against the edges of the sheets at the upper portion of the stack.
7. The combination with a vertical feeding device for a pack of plates and feed members in advance of such device, of feed means comprising electromagnetic lifting means above the pack and an electric circuit for energizing said electromagnetic lifting means, a rotating magnet also located above the pack adapted by the rotation to feed the top plate of the pack forwardly, automatic means for intermittently making and breaking the circuit energizing said electromagnetic means, means for continuously applying air under pressure against the edges of the sheets at the upper portion of the pack, and means intermittently applying blasts of air beneath the top sheets of the pack as they are successively lifted by 45 said electromagnetic means.
8. The combination with a pair of rolls and a feed device to the rear thereof for lifting the top members of a pack of plates and feeding them forwardly between said rolls, of a supporting framework for said feed device open on one side to permit a truck carrying a base with a pack of plates thereon to be moved into position beneath said feed device, elevating means carried by the framework adapted to lift the base and pack from the truck, and automatic means operating in timed relation with feed device for lifting the pack step by step as the sheets are removed from the top of the pack.
9. The combination with a vertical feeding device for a pack of plates and feed members in advance of such device, of feed means comprising electromagnetic lifting means above the pack and an electric circuit for energizing said electro-magnetic lifting means, a rotating magnet also located above the pack adapted by its rotation to feed the top plate of the pack forwardly, and automatic means for intermittently making and breaking the circuit energizing said electromagnetic means, timed so that the electromagnetic lifting means release the lifted top plate just before it is engaged.

and fed forward by the rotating magnet, the said rotating magnet having its pole arranged radially with respect to its axis of rotation.

- 5 10. The combination with a vertical feeding device for a pack of plates and feed members in advance of such device, of feed means comprising an electromagnet above each corner of the top plate of the pack 10 and an electric circuit for energizing said electromagnets, a rotating constantly energized magnet also located above the pack adapted by its rotation to strike the plate lifted from the pack by said electro-magnets 15 and feed it forwardly, and automatic means for intermittently making and breaking the circuit energizing the windings of the said electromagnets, the said rotating magnet having its pole arranged radially with respect to its axis of rotation.

11. The combination with a vertical feeding device for a pack of plates and feed members in advance of such device, of feed means comprising an electromagnet above each corner of the top plate of the pack and an electric circuit for energizing said electromagnets, a rotating constantly energized magnet also located above the pack adjacent the forward edge thereof and adapted by its rotation to strike the plate lifted from the pack of said electro-magnets and feed it forwardly, and automatic means for intermittently making and breaking the circuit energizing the windings of the said electromagnets, the said rotating magnet having its pole arranged radially with respect to its axis of rotation.

12. The combination with a vertical feeding device for a pack of plates and feed members in advance of such device, of feed means comprising an electromagnet above each corner of the top plate of the pack and an electric circuit for energizing said electromagnets, a rotating constantly energized magnet also located above the pack adapted by its rotation to strike the plate lifted from the pack by said electro-magnets and feed it forwardly, and automatic means for intermittently making and breaking the circuit energizing the windings of the said electromagnets, timed so that the electromagnets release the lifted top plate before it is engaged and fed forwardly by the rotating magnet, the said rotating magnet having its pole arranged radially with respect to its axis of rotation.

13. The combination with a vertical feeding device for a pack of plates and feed members in advance of such device, of feed

means comprising electromagnetic lifting means above the pack and an electric circuit for energizing said electro-magnetic lifting means, a rotating magnet also located above the pack adapted by its rotation to feed the top plate of the pack forwardly, automatic means for intermittently making and breaking the circuit energizing said electro-magnetic means, and means intermittently applying blasts of air beneath the top sheets of the pack as they are successively lifted by said electromagnetic means, the said means for intermittently applying the blasts of air including a flexible supply pipe and automatic means for pinching such pipe and releasing it at timed intervals.

14. The combination with a vertical feeding device for a pack of plates and feed members in advance of such device, of feed means comprising electromagnetic lifting means above the pack and an electric circuit for energizing said electro-magnetic lifting means, a rotating magnet also located above the pack adapted by its rotation to feed the top plate of the pack forwardly, automatic means for intermittently making and breaking the circuit energizing said electromagnetic means, and means intermittently applying blasts of air beneath the top sheets of the pack as they are successively lifted by said electromagnetic means, the said means for intermittently applying the blasts of air including a flexible supply pipe and cam actuated automatic means for pinching such pipe and releasing it at timed intervals.

15. The combination with a vertical feeding device for a pack of plates and feed members in advance of such device, of feed means comprising a pair of electromagnetic lifting devices above the rear portion of the pack adjacent the side edges thereof, an electric circuit for energizing said lifting devices, a holding member located above the extreme rear portion of the pack at the central portion thereof arranged to hold the central portion of the top sheet down against the sheet of the pack next beneath when the side edges of such top plate are lifted, a rotating magnet also located above the pack adapted by its rotation to feed the top plate of the pack forwardly, and automatic means for intermittently making and breaking the circuit energizing said electro-magnetic lifting devices.

In testimony whereof, I have hereunto subscribed my name this 20th day of Nov., 1924.

CHARLES FINIGAN.
